UNITED STATES PATENT OFFICE.

PERCY I. ANSORGE, OF BROOKLYN, NEW YORK.

DESIGN FOR A LIGHTING-FIXTURE PART.

Application filed August 1, 1922. Serial No. 3,261. Term of patent 7 years.

To all whom it may concern:

Be it known that I, PERCY I. ANSORGE, a citizen of the United States, residing at 787 E. 5th St., borough of Brooklyn, in the city of New York, county of Kings, and State of New York, have invented a new, original, and ornamental Design for Lighting-Fixture Part, of which the following is a specification, reference being had to the accompanying drawing, forming part thereof.

Figure 1 is a side view of my new design.

Figure 2 is a front view of my new design of an ornamental plate for lights, comprising back plate as shown with two arms projections or supports for lights extending from and forming part of this ornamental plate as shown.

I claim:

The ornamental design for a lighting fixture part as shown and described.

PERCY I. ANSORGE.
